UNITED STATES PATENT OFFICE.

JOHN C. LEFFEL, OF SHELBINA, MISSOURI, ASSIGNOR OF ONE HALF HIS
RIGHT TO SETH V. LEFFEL.

IMPROVEMENT IN HAND CORN-PLANTERS.

Specification forming part of Letters Patent No. **152,563**, dated June 30, 1874; application filed
March 30, 1874.

To all whom it may concern:

Be it known that I, JNO. C. LEFFEL, of Shelbina, in the county of Shelby and State of Missouri, have invented certain new and useful Improvements in Hand Corn-Planters; and I do hereby declare the following to be a full, clear, and exact description of the invention, such as will enable others skilled in the art to which it appertains to make and use it, reference being had to the accompanying drawings, which form part of this specification.

The nature of my invention consists in the construction and arrangement of a hand corn-planter, as will be hereinafter more fully set forth.

In order to enable others skilled in the art to which my invention appertains to make and use the same, I will now proceed to describe its construction and operation, referring to the annexed drawing, which represents my invention.

Figure 1 is a vertical section of my invention. Figs. 2 and 3 are detail views of the same.

A represents the box in which the corn to be planted is placed, said box being attached to a board, B. From the bottom of the box A leads a conveyer, C, to a foot or cutter, D, the box-board B extending down into said foot. Through the conveyer C and lower part of the board B are three channels, *a a*, through which the corn is dropped. The lower ends of these channels are such distances apart—say, three inches, more or less—as to deposit the corn the proper distance apart, and thereby save the labor of thinning out. The rear plate D' of the foot or cutter D is hinged thereto, and provided with an arm, E, which extends up along the box-board B, and has at its upper end a suitable handle, by means of which it is operated. In the bottom of the box A is a horizontal slide, G, the rear end of which has a short tongue, *b*, projecting through a slot in the arm E. Through the end of the tongue *b* passes a pin, *d*, upon which are placed two friction-rollers, *e e*, working in grooves on the back of the arm E. As this arm is moved out and in upon its hinge, carrying with it the slide G, the rollers *e e* move up and down in their grooves, maintaining the slide always in a horizontal position. Heretofore, in this class of corn-planters, there has

always been a joint of some kind in, or connected to, the slide, so as to allow for the curve in opening and closing the planter; but by my construction of this part of the planter such joint is obviated, and I am enabled to use a perfectly solid and stiff slide, and still cause it to move perfectly level in the box. The slide G has three holes or cells, *i i*, corresponding with the upper ends of the channels *a a*. Above the slide in the box-board B is made a passage for a three-pronged punch, *f*, which, when the slide is drawn out, drops down and forces the corn out of the cells *i i*, and prevents it from sticking therein. The outer ends or sides of these cells are beveled, so that when the slide is moved inward again the punch *f* will rise out of the cells again and be ready to drop at the next outward movement of the slide. Inside of the box A is a cut-off formed of a piece of leather, *h*, with a flat spring, *m*, pressing on the upper part thereof. Across the box, a short distance above the slide, is a wire, *n*, to flatten the seed so that the cells can receive it. *p* is a half cut-off arranged on the back of the box to assist in filling the cells.

I am aware that different devices have been used, in walking-planters, to force the grains through a revolving seed-plate, and this I disclaim.

Having thus fully described my invention, what I claim as new, and desire to secure by Letters Patent, is—

1. In a hand corn-planter, the pronged punch *f*, inserted through the board B, in combination with the slide G, the parts being combined to operate as set forth.

2. A hand corn-planter composed of the boards B D, box A, slide G, having the rollers *e* upon its end, punch *f*, and cut-offs *p m*, the parts being combined for operation substantially as shown and described.

3. The combination of the cut-off *h* with spring *m*, the wire *n*, and the half cut-off *p*, all arranged within the box A, substantially as and for the purposes herein set forth.

In testimony that I claim the foregoing, I have hereunto set my hand this 23d day of March, 1874.
